COMBINED POUR SPOUT AND HANGER FOR A CONTAINER

Joseph Marg, 24043 Greenlawn Ave.,
Beachwood, Ohio 44121

Original design application Feb. 5, 1969, Ser. No. 15,640.
Divided and this application Nov. 16, 1970, Ser. No.
25,980

Term of patent 14 years

Int. Cl. D9—07

U.S. Cl. D9—290

Fig. 2

Fig. 3

Fig. 1

FIG. 1 is a perspective view of a combined pour spout and hanger for a container showing my new design;

FIG. 2 is a top plan view; and

FIG. 3 is an elevational view thereof.

The bottom is plain and unornamented.

This application is a division of design application, Ser. No. D. 15,640 filed Feb. 5, 1969.

I claim:

The ornamental design for a combined pour spout and hanger for a container, as shown and described.
